UNITED STATES PATENT OFFICE.

GEORGE F. GREENE, OF PROVIDENCE, RHODE ISLAND.

DESIGN FOR A SCARF-PIN.

SPECIFICATION forming part of Design No. 23,755, dated November 6, 1894.

Application filed October 6, 1894. Serial No. 525,168. Term of patent 3½ years.

To all whom it may concern:

Be it known that I, GEORGE F. GREENE, a citizen of the United States, residing at Providence, in the county of Providence and State of Rhode Island, have invented and produced a new and original Design for Scarf-Pins, of which the following is a specification, reference being had to the accompanying drawing, forming a part thereof.

10 The head or ornamental portion of the scarf-pin has the outline, shape and appearance of a frog, in front view and upright grotesque position, standing upon its hind legs which are sprawled and bent outwardly at a sharp angle and his webbed feet are broadly extended. His head appears thrown far back. 15 His front legs appear as arms, the left one extending outwardly but bent sharply up-

ward and supporting a sailor hat, the right extending outwardly but bent sharply downward with spread webbed fingers from which a cane reaches at an angle inwardly. The figure is attired in breeches extending half way down to the knees and from the waistband thereof are suspenders reaching up to the shoulders. A bowed necktie appears at the neck. The pin tongue extends centrally downward from said ornamental portion or head.

20 What I claim is—

25 The design for a scarf-pin herein shown and described.

GEORGE F. GREENE.
